OTHER PUBLICATIONS

Japanese Patent Office, Office Action in connection with design application serial No. D 2010-013870, rejecting the subject design based on the publication of the product on Amazon.com (see attached photograph) on Jun. 22, 2009.

Primary Examiner — Ian Simmons

Assistant Examiner — Carissa C Fitts

(74) Attorney, Agent, or Firm — Gottlieb, Rackman & Reisman PC

(57) **CLAIM**

The ornamental design for an illuminating placard, as shown and described.

DESCRIPTION

FIG. 1 is a top, front and right side perspective view of an illuminating placard showing my new design;

FIG. 2 is a front elevational view thereof, the rear elevational view being a mirror image;

FIG. 3 is a right side view thereof, the left side view being a mirror image;

FIG. 4 is a top plan view thereof; and,

FIG. 5 is a bottom plan view thereof.

1 Claim, 3 Drawing Sheets# US D653,372 S
